Term of patent 14 years

(Cl. D52—2)

FIG. 1

FIG. 2

FIG. 3

FIG. 4

FIG. 5

FIG. 6

FIG. 1 is a perspective view of a dispenser for rolled paper showing my new design;

FIG. 2 is a top plan view of the dispenser shown in FIG. 1;

FIG. 3 is an end view thereof taken from the right of FIG. 1;

FIG. 4 is a bottom view of the dispenser shown in FIG. 1;

FIG. 5 is a vertical sectional view of the dispenser taken generally as indicated by the line 5—5 in FIG. 1, and

FIG. 6 is a fragmentary sectional view of the dispenser taken generally as indicated by the lines 6—6 in FIG. 3.

The essential features of the design reside in the portions shown in full lines.

The rear of the dispenser is hollow.

I claim:

The ornamental design for a dispenser for rolled paper or the like, as shown and described.
